CRACKING HYDROCARBON OIL

Victor Stapleton, New York, N. Y., assignor to
The Texas Company, New York, N. Y., a corporation of Delaware

Application October 25, 1935, Serial No. 46,642

3 Claims. (Cl. 196—58)

This invention relates to the art of cracking hydrocarbon oil wherein higher boiling hydrocarbons are converted into lower boiling products and pertains more particularly to a method of and apparatus for merging highly heated streams of hydrocarbon products.

While my invention has a more general application it has been found to have particular advantages when used in a process of cracking hydrocarbon oil of the general nature disclosed in an earlier co-pending application, Serial No. 24,794, filed jointly by myself and Claude E. Watson.

It is the natural desiderata of all oil-cracking processes to produce the maximum yield of the best quality gasoline from the raw charging stock in the most economical manner. The increase in compression ratio of internal combustion motors has necessitated the placing of more emphasis on the quality and particularly the non-detonating or anti-knock properties of the gasoline produced.

It is a demonstrated fact that gasolines produced as a result of high-temperature, high crack per pass cracking operations have, as a general rule, materially better non-detonating characteristics than gasoline resulting from simple distillation or from low-temperature cracking treatment. In view of this, the trend is to avoid cracking at low temperatures insofar as possible. To meet present day requirements in this respect it is usually considered desirable to carry out the cracking reaction at temperatures upwards of 850° F., for example.

There are, however, certain heavy black oil stocks which are susceptible to cracking, such as cracked or crude residuals, but which, because of their tendency to form troublesome coke deposits within the equipment, are not amenable to high-temperature cracking treatment in the normal manner by being passed through a tubular coil in a heating zone.

In the application above identified filed jointly by myself and Claude E. Watson there is described a method of cracking wherein these heavy black oils are rapidly heated to high cracking temperature by direct admixture with more highly heated cracked products from a tubular heating coil employed for high temperature cracking of a relatively cleaner stock such as gas oil. The admixed products are passed to an enlarged reaction chamber wherein the vapors separate from unvaporized liquid residuum. The liquid residuum, after being subjected to high-temperature cracking for only a relatively short time is removed from the chamber without allowing any

substantial accumulation of liquid therein, while the vapors are subjected to prolonged conversion treatment at a temperature sufficiently high to produce high-grade anti-knock gasoline.

When operating in this manner it was found, contrary to what might be expected, that less coking troubles were encountered and longer operating runs were realized than was the case when only clean condensate stocks were subjected to cracking treatment without admixture with heavier black oil.

With the use of only lighter, vaporizable stocks in the treatment troubles developed in the region of the tar outlet from the reaction chamber. This was surprising in view of the fact that heavy black oil contains constituents unvaporizable under conditions obtaining within the reaction chamber and which normally have a greater tendency to form coke than the more volatile oil.

While it was found that coking troubles in this region of the reaction chamber were avoided when admixing heavy black oil containing unvaporizable constituents with the cracked vapor products passing to the reaction chamber so as to maintain a condition of liquidity in the region of the tar outlet from the chamber, other coking troubles at times developed in the transfer line between the point of merger of the black oil stream with the highly heated products from the cracking coil and the reaction chamber. While these troubles do not always develop at this point it has been encountered at times when operating on certain Mid-Continent crude stocks, for example. In some cases a ring of coke was found to have formed immediately adjacent the connection joining the two streams and in other cases at other points on the down-stream side of the connection.

While the reason for the formation of coke in this region of the transfer line has not been definitely established, I have reason to believe that it is due to alternate drying and wetting of the pipe surface by the products passing therethrough. When the connecting pipes are joined to each other by a simple connection such as by a T or Y connection the two streams do not instantly become thoroughly mixed so that the surface of the pipe line immediately adjacent the connection on the down-stream side and at other points in the transfer line may be washed with relatively dry vapors from the heating coil during one instant of time and with a relatively cooler and heavier liquid from the other stream at other times. This alternate wetting and drying of the surface of the pipe is believed to be the

cause of the building up of the coke ring at this point in the line.

The object of the present invention is to provide a method of and an apparatus for merging the two streams of oil hereinbefore described so as to avoid coking difficulty within this region.

According to my invention a heavy black oil stream containing constituents unvaporizable under conditions obtaining within the reaction chamber is caused to merge with more highly heated products from a cracking coil in a specially constructed connection wherein the two streams are caused to first pass in concentric relation to each other for a short time, and the outer concentric stream is then caused to be deflected into the inner stream to effect a rapid and intimate mixture thereof.

Further, in accordance with my invention, it is preferred to mount this specially constructed connection directly at the point of entrance into the reaction chamber so that the two streams, after being intimately mixed, pass directly into the chamber without passing through an additional pipe line. In accordance with this preferred form 25 the relatively cooler black oil stream is passed in outer concentric relation to the more highly heated products from the heating zone so that the metal wall of the chamber surrounding the connections is maintained at the temperature of 30 the cooler stream rather than at the higher temperature of the products from the heating zone, and localized stresses in this region of the vessel are avoided.

Further objects and advantages of my invention will become apparent from the more detailed description hereinafter in which reference will be made to the accompanying drawing.

In the drawing Figure 1 is a diagrammatic illustration of an oil-cracking apparatus for carrying out a process of the general nature hereinbefore described, and Figure 2 is a detailed sectional view of the special connection for merging the two oil streams.

Referring to Figure 1 of the drawing, a relatively clean vaporizable stock is passed through a tubular heating coil 10 located within the furnace 11, and the hot cracked products from the heating coil 10 are then passed through the transfer line 12 to a connection 13 wherein they 45 are merged with a relatively cooler black oil stream from the line 14. The combined stream of oil then passes into the reaction chamber 15 wherein further conversion is attained. The charging stock for the cracking coil 10 may consist in whole or in part of a condensate stock such as Mid-Continent gas oil from an extraneous source introduced into the system through line 16 or may consist in whole or in part of reflux condensate formed in the process as 50 hereinafter described. The black oil stream may comprise a residual stock such as crude or reduced crude or other heavy fractions preferably containing constituents unvaporizable under conditions obtaining in the reaction chamber 15. 55 This stock, preferably preheated to a temperature of the order of 600° to 800° F., may be introduced directly into the line 14 through connection 17, or may be a product of the process hereinafter described or a mixture of both.

As shown in Figure 2 the end of the pipe 12 carrying the hot products from the heating coil projects downwardly into an enlarged sleeve 18 which in turn extends through an opening in the 70 wall of the reaction chamber 15 and is welded 75 to the surrounding wall of the reaction chamber

to form a pressure-tight seal. The sleeve 18 is of somewhat larger diameter than the pipe 12 throughout the greater portion of its length to form an annular space into which the cooler black oil stream from the pipe 14 discharges. The outer end of the sleeve 18 is of reduced diameter to fit tightly around the pipe 12 and is welded thereto by means of plug welds 19 and a circumferential fillet weld 20 to form a fluid-tight seal. The inner end of the sleeve 18 extends somewhat beyond the end of the pipe 12 and is flared inwardly to form an annular nozzle for projecting the outer black oil stream into the central stream of highly heated products from the heating coil.

By merging the two streams directly at the point of entrance into the reaction chamber so as to effect a rapid and thorough intermixture of the two streams in the manner hereinbefore described the black oil stream may be rapidly heated to a relatively high cracking temperature sufficient to effect a high rate of cracking per pass and produce high grade anti-knock gasoline with minimum cracking of this stock in the low-temperature range.

The unvaporizable constituents of the heavy black oil and any liquid polymers which may be formed during the cracking of the lighter condensate immediately separate from the vapors upon being introduced into the reaction chamber 30 and drop to the bottom of the reaction chamber and are withdrawn therefrom through line 21 at a rate which will prevent a substantial accumulation of liquid being formed therein. In addition to subjecting the black oil to short time cracking 35 at high temperature the unvaporizable constituents thereof perform an important function of maintaining a condition of liquidity in the region of outlet 21 and serve to reduce coking troubles within this region of the chamber.

Moreover, by passing the black oil stream through the connection in outer concentric relation to the more highly heated products from the cracking coil the vessel wall surrounding the sleeve is maintained at lower temperature, and differential stresses within this region of the vessel 40 are avoided.

The liquid withdrawn from the bottom of the reaction chamber 15 through line 21 may be cooled and sent to storage or may be further distilled either by reduction in pressure or by additional heat or both, and the heat of the vapors liberated during the distillation may be employed directly or indirectly for preheating fresh heavy charge for the process all in a manner well known 55 in the art and which, consequently, has not been shown on the drawing.

The vapors separated from the liquid within the reaction chamber 15, after being subjected to the desired conversion treatment at relatively 60 high cracking temperature, such as upwards of 850° F., for example, within the chamber, are withdrawn therefrom through line 22 and pass to suitable fractionating equipment for separation into desired fractions.

While I have shown for purpose of illustration, and prefer a reaction chamber of the downflow type, wherein the vapors pass in a downward direction, it will be understood that an upflow type of chamber, or a plurality of chambers arranged 70 in parallel or in series through which the vapors pass in the same or opposite directions may be employed.

Further, by way of illustration, I have shown the fractionating equipment for the cracked va- 75

5 pores as comprising a primary fractionating tower 23 and a secondary fractionating tower 24 connected by vapor line 25. By having two fractionating zones the heavy charging stock, which preferably 10 contains unvaporizable crude residuals such as crude or reduced crude and which may be preheated in any desired manner, such as by direct or indirect contact constituents contained in the liquid withdrawn from the bottom of reaction chamber 15 through line 21, as hereinbefore described, may be introduced into the primary fractionating tower 23 at an intermediate point thereof. In this event the bottoms from the primary fractionating tower may be passed through lines 26, 27 and pump 28 to line 14 and 15 constitute a part or all of the heavy black oil stream merged with the products of the cracking coil in connection 13.

20 Clean condensate formed in the secondary fractionating tower is withdrawn therefrom through line 29, and may be passed through line 30, pump 31 and line 32 to the heating coil 10 and constitute a part or all of the charging stock therefor.

25 Vapors remaining uncondensed in the secondary tower 24 may be passed through line 33 to a condenser 34 wherein the desired gasoline distillate from the process is condensed, and the products then pass to receiver 35 wherein the distillate separates from fixed gases in the customary manner.

30 As an example of temperature conditions which may be maintained in the cracking portion of the equipment, in order to realize the greatest advantages from my invention, the outlet of the heating coil may be held at a temperature upwards of 950° F. and preferably from 975° to 1000° F. or higher. The reaction chamber is preferably maintained upwards of 850° F. and preferably at 40 from 860° F. to 925° F. The maximum temperatures maintained in this portion of the equipment as a practical matter are limited to temperatures sufficiently low to maintain a condition of liquidity in the bottom of the reaction chamber.

45 The amount of preheating of the black oil before merging with the products from the heating coil will depend upon the character of the stock and the manner and rate of heating. For example, when introducing crude or reduced crude into the primary fractionating tower and using the bottoms from the tower as the black oil stock, as shown in the drawing, and wherein the fresh oil is rapidly heated by direct contact with cracked vapors undergoing fractionation, the black oil may be preheated to a temperature as high as 800° F. providing the bottoms are not permitted to remain at this temperature for any substantial length of time. In this connection it will be understood that one of the objectives is to avoid low-temperature cracking in the process insofar as possible.

50 The pressure maintained on the cracking portion of the equipment, wherein my improvement lies, may vary over a relatively wide range. As a matter of practice it is usually desirable to maintain a superatmospheric pressure such as from 200 to 400 or more pounds per square inch so that velocity of flow of the products through the equipment may be more closely regulated. The reaction chamber may be maintained at substantially the same pressure as the outlet of the heating coil, except for the necessary drop to effect the desired flow, or a substantial differential pressure between the coil and reaction chamber may be maintained by a suitable reducing valve.

55 However, a substantial superatmospheric pres-

sure within the reaction chamber is helpful in maintaining a condition of liquidity at the outlet of the reaction chamber.

60 When operating in accordance with my invention, coking trouble in the transfer line on the downstream side of the connection, joining the black oil stream and cracked products from the heating coil, has been completely avoided so that in no case has coking in this region of the equipment limited the length of operating runs, whereas in certain cases, particularly when treating certain Mid-Continent crudes, coking in the transfer line has been the cause of premature discontinuance of the process in prior practices of this nature.

65 While my invention has been found to have particular advantage in the process before described, it may have other applications. Having thus described the preferred embodiment, it is understood that my invention embraces such other variations and modifications as come within the spirit and scope thereof and that it is not my intention to dedicate any novel features thereof or to limit the invention except as necessary to distinguish from prior art.

70 I claim:

75 1. The method of cracking hydrocarbon oils, in an apparatus comprising a heating coil and a communicating enlarged reaction chamber, that comprises heating a condensate oil in transit through the heating coil to a high cracking temperature, delivering a stream of resultant highly heated products from said coil into the upper portion of said enlarged reaction chamber, combining a cooler stream of charging stock comprising residual constituents of crude petroleum with said stream of highly heated products in such manner that no restriction of the mixture occurs during or substantially after admixture by bringing the streams together directly at the point of entry of the same into said enlarged reaction chamber to thereby raise said charging stock to a desired cracking temperature, passing the commingled products downwardly in said reaction chamber while maintaining them at a cracking temperature under superatmospheric pressure and withdrawing liquid from the lower portion of the chamber at a rate adequate to prevent the accumulation of liquid therein.

80 2. The method of cracking hydrocarbon oils, in an apparatus comprising a heating coil and a communicating enlarged reaction chamber, that comprises heating a condensate oil in transit through the heating coil to a high cracking temperature, delivering a stream of resultant highly heated products from said coil into the upper portion of said enlarged reaction chamber, combining a cooler stream of charging stock comprising residual constituents of crude petroleum with said stream of highly heated products in such manner that no restriction of the mixture occurs during or substantially after admixture by bringing the streams together directly at the point of entry of the same into said enlarged reaction chamber to thereby raise said charging stock to a desired cracking temperature, passing the commingled products downwardly in said reaction chamber while maintaining them at a cracking temperature under superatmospheric pressure, separately withdrawing vapors from a lower portion of said reaction chamber and separately withdrawing liquid from a point below that at which said vapors are withdrawn at a rate adequate to prevent accumulation of liquid therein.

3. The method of cracking hydrocarbon oils, in an apparatus comprising a heating coil and a communicating enlarged reaction chamber, that comprises heating a condensate oil in transit through the heating coil to a high cracking temperature, delivering a stream of resultant highly heated products from said coil into the upper portion of said enlarged reaction chamber, introducing a cooler stream of charging stock comprising residual constituents of crude petroleum into the upper portion of said enlarged reaction chamber and causing said stream of charging stock to flow in outer concentric relation to the stream of highly heated products from the heating coil while the streams are passing through

the inlet opening in the wall of said reaction chamber and merging the two concentric streams in such manner that no restriction of the mixture occurs during or substantially after admixture by bringing the streams together directly at the point of entry into the reaction chamber to thereby raise said charging stock to a desired cracking temperature, passing the commingled products downwardly in said reaction chamber while maintaining them at a cracking temperature under superatmospheric pressure and withdrawing liquid from the lower portion of the chamber at a rate adequate to prevent the accumulation of liquid therein.
